UNITED STATES PATENT OFFICE

167,912

GIRDLE

Alan C. Spero, Great Neck, N. Y., assignor to Enchantress Foundations, Inc., Great Neck, N. Y., a corporation

Application May 23, 1952, Serial No. 19,843

Term of patent 3½ years

(Cl. D20—2)

To all whom it may concern:

Be it known that I, Alan C. Spero, a citizen of the United States, residing at 258 Shoreward Drive, village of Great Neck, county of Nassau, State of New York, have invented a new, original, and ornamental Design for a Girdle, of which the following is a specification, reference being had to the accompanying drawing, forming a part thereof. Figure 1 is a front view of the girdle, showing my new design. Figure 2 is a rear view of the girdle.

I claim:

The ornamental design for a girdle, as shown.
ALAN C. SPERO,
